MITERING MACHINE

Filed Dec. 22, 1939

Inventor:
William J. Knoll.
By Free & Free Atty.

UNITED STATES PATENT OFFICE

2,282,064

MITERING MACHINE

William Jacob Knoll, Chicago, Ill., assignor to
 H. B. Rouse & Company, Chicago, Ill., a corporation of Illinois

Application December 22, 1939, Serial No. 310,583

5 Claims. (Cl. 90—15)

The invention relates generally to devices for mitering printers' rules and more particularly to an improved carriage for holding the rule while being mitered.

The invention has among its objects the production of such a device which is constructed of relatively few parts, very durable and very efficient for the purpose intended.

Another object of the invention is the production of rule holding means which may be operated in a minimum amount of time and in which adjustments for various sized rules are unnecessary.

A further object of the invention is the construction of such a holder in which the clamping pressure is increased for rules of greater thickness and diminished for very thin rules.

Many other objects and advantages of the construction herein shown and described will be obvious to those skilled in the art from the disclosure herein given.

To this end my invention consists in the novel construction, arrangement, and combination of parts herein shown and described and more particularly pointed out in the claims.

In the drawing wherein like reference characters indicate like or corresponding parts:

Fig. 1 is a side elevational view of a mitering machine embodying the present invention with portions thereof broken away;

Fig. 2 is a plan sectional view through the clamping or holding mechanism; and

Fig. 3 is an elevational view in section of the clamping mechanism.

It has been customary in machines for mitering printers' rules to employ a carriage or holder for holding the rule while it is being mitered. These holders have, in the past, utilized an ordinary screw type clamp or the like to carry the rule. By rotating a knob in one direction, the clamping means was opened to receive the rule, and by rotating the knob in the opposite direction, the clamp was screwed down to grip the rule.

With the present invention, the clamp is spring operated, the operating handle or knob merely being moved inwardly to allow the clamping portion to receive or release the rule. When the knob is returned to its original position, the rule will be securely held in place. Obviously, such a holder may be operated more quickly than one requiring the turning or unscrewing of a knob to operate the clamping means.

Illustrated is a mitering machine of more or less general style comprising a base 1 upon which is carried stationary uprights 2. Slidably in the

uprights is a bearing block 3 having a cutter 4 journaled therein, the latter driven by means of a pulley and belt 6 from a suitable power source. The bearing block 3 is moved into and out of cutting position by means of a handle 7 pivotally connected at 8 to the upright 2 and to the bearing block by means of a link 9. A tension spring 10 secured at one end to the base and at the opposite end to the handle returns and maintains the cutter in non-cutting position. Secured to the base 1 is a cross head 11. The latter is provided with a channel or groove 12 in the upper end thereof of a size to receive a block 13, said block being slidable therein. Extending from one end of the block on opposite sides thereof are a pair of clamping jaws 14, the latter being generally L-shaped and engageable with the platen bar 15 which is secured to and carried by the cross head. A plate 16 extends laterally from the cross head adjacent the bottom of the platen bar 15 forming supporting means for the rule 17 while the cutter 4 moves downwardly to miter the same, the cutter passing intermediate the two jaws 14. Thus, the rule is securely held in place on opposite sides of the cutter. Extending from the end of the block 13 opposite the jaws 14, and secured thereto by a pin 18 is a stem 19, the latter passing through a collar 21 attached to the cross head 11 by screws 22. A knob 23 is secured to the end of the stem 19 by a screw 24. The collar 21 is provided with a bore 25 of a size to receive a compression spring 26, the latter seating at one end against the knob 23 and at the other end against the inwardly extending flange 27 of the collar. Thus, it will be seen that the spring 26 urges the stem 19 and block 13 to force the jaws 14 into engagement with the platen bar 15. A cap plate 28 is secured to the cross head 11 by any suitable means such as screws 29 and covers the channel 12.

In use, the knob 23 is merely pushed inwardly towards the cross head compressing the spring 26 and moving the jaws 14 away from the platen bar 15, thereby allowing the insertion of the rule between the same, the rule resting upon the plate 16. Upon releasing the knob, the spring 26 will force the jaws 14 outwardly, clamping the rule between the jaws and the platen bar.

It will be noted that the jaws 14 will grip a thick rule more strongly than a thin rule due to the increase in spring compression, thereby preventing damaging of thin rules. As the only operation necessary to lock or release the rule is to position the knob 21 inwardly or release the same, operation is speeded up considerably, there being no knobs to tighten or unscrew. Likewise, as

there are few parts, the device is very durable, there being no parts to adjust or the like.

Having thus described my invention, it is obvious that various immaterial modifications may be made in the same without departing from the spirit or scope of my invention; hence, I do not wish to be understood as limiting myself to the exact form, construction, arrangement, and combination of parts herein shown and described or uses mentioned.

What I claim as new and desire to secure by Letters Patent is:

1. In a rule mitering machine, the combination of a cutter, a cross head operatively related thereto and having a channel therein, a jaw slidably carried in said channel, a platen bar extending transversely to said cutter in opposition to said jaw, and resilient means for urging the jaw and bar into clamping relation for clamping a rule therebetween while engaged with the cutter.

2. In a device of the kind described, the combination of a cutter, a supporting member operatively related thereto, a jaw carried by said member, a platen bar carried by said member and extending transversely to said cutter in opposition to said jaw, and resilient means for urging said jaw and bar in clamping relation for clamping a rule therebetween while the latter is engaged with the cutter.

3. In a device of the kind described, a supporting member having a channel in the upper surface thereof, a block slidably carried in said channel, a pair of L-shaped jaws carried by said block

and extending beyond said channel, a platen bar mounted on said supporting member above the horizontal portions of said jaws in opposed relation to vertical portions of the same, a stem secured to said block, and a spring operatively related to said supporting member and stem for urging said block in a direction to draw said jaws toward said platen bar for clamping a rule therebetween.

4. In a device of the kind described, a supporting member having a channel therein, a block slidable in said channel, jaws carried by said block, a platen bar carried by said member in opposed relation to said jaws, a stem extending from said block, a handle on said stem, and a spring operatively related to said stem and member for urging said jaws toward said bar for clamping a rule therebetween.

5. In a device of the kind described, a supporting member having a channel therein, a block slidable in said channel, jaws extending from one side of said block, a stem extending from the opposite side of said block, a platen bar carried by said member in opposed relation to said jaws, said jaws and bar operative to clamp a rule therebetween, a collar surrounding said stem and secured to said member, said stem terminating in a knob, a compression spring encircling said stem and engageable at its ends with said collar and knob, respectively, to draw said jaws toward said platen bar.

WILLIAM JACOB KNOLL.
